UNITED STATES PATENT OFFICE.

OLIVER W. KEARNS, OF DAYTON, OHIO.

DESIGN FOR A DISPLAY STAND.

Application filed February 25, 1928. Serial No. 25,586. Term of patent 7 years.

To all whom it may concern:

Be it known that I, OLIVER W. KEARNS, a citizen of the United States, residing at Dayton, in the county of Montgomery and State of Ohio, have invented a new, original, and ornamental Design for Display Stands, of which the following is a specification, reference being had to the accompanying drawing, forming part hereof.

The figure is a perspective view of a display stand, showing my new design.

I claim:

The ornamental design for a display stand, as shown.

OLIVER W. KEARNS.
